EXTENSIBLE SAFETY SUSPENDERS

Filed July 4, 1945

UNITED STATES PATENT OFFICE

2,452,538

EXTENSIBLE SAFETY SUSPENDERS

Roy S. Ashton, Brooklyn, N. Y.

Application July 4, 1945, Serial No. 603,141

1 Claim. (Cl. 2—325)

1

This invention relates to suspenders for supporting trousers. Its objects are to provide a pair of suspenders with means for quickly and easily extending the length of the supporting straps so that the user may drop his trousers without taking off his coat and vest to attend to the call of nature without exposing his body to the chilling influence of an unheated toilet or exposing valuables in the pockets of his coat and vest to loss or theft; or without detaching the suspenders from the trousers at any point; and without loss of valuable time in cases of emergency.

Another object of the invention is to combine these advantages in a pair of suspenders having standard features of construction and service, which will permit of the manufacture of the suspenders with standard equipment, to be merchandised by the usual methods of marketing.

With the above and other objects in view, the invention relates to certain new and useful constructions, combinations and arrangements of parts, clearly described in the following specification, and fully illustrated in the accompanying drawings, in which:

Fig. 1 is a front view, showing the improved suspenders applied to a user, with the front legs or supporting webs of the suspenders in their normal trousers-supporting positions.

Fig. 2 is a similar view, showing the front legs or webs of the suspenders extended to permit of the quick lowering of the trousers.

Fig. 3 is a detail front elevation, broken away, of one of the connectors.

Fig. 4 is a side elevation thereof.

Fig. 5 shows an alternative arrangement of the back straps or webs of the suspenders, with connecting cross-piece.

Fig. 6 is a fragmentary front view of a modified slip connector.

Referring to the accompanying drawings, which illustrate the practical embodiment of my invention, 5 designates one front leg or strap and 6 the other front leg or strap of the suspenders. Strap 5 passes through the slot or loop 17 of the trousers-connecting fixture 18, which may be of any suitable construction to engage the waistband of the trousers or to engage the usual button on the waistband; then upward as a long parallel extension 12, terminating with a snap button or connector 13, adapted to engage the matching snap button element or connector 14, carried by the slide 15. This slide is adjustable in height on the strap 5 by means of the lever clamp 16, which may be of conventional con-

2

struction and which is pivoted at 16a to the slide, so that the short arm of the lever will have pressure engagement with the strap.

Strap 6 is of similar construction, being provided with an extension 19, terminating with a connector or snap button element 20, which is adapted to engage a matching element or connector carried by the slide 21, which is adjustable in height on the strap by means of the pivoted lever clamp 22.

The straps 5 and 6 are continued upward and rearwardly over the shoulders in the usual manner 7 and 8 and then down the back as the back legs or straps 9 and 10, shown in dotted lines. Each strap then passes through the slot or loop of its corresponding trousers-connecting fixture 11, then upward as a parallel extension terminating by attachment to the slide buckle 11a or 11b. These slide buckles, mounted in any suitable manner on the back legs or straps 9 and 10, are adjustable to any desired fixed height, thus regulating the tension or pull exerted by the suspenders on the trousers.

The back legs or straps 9 and 10 are in crossed relationship, as in the usual or conventional suspenders, for the purpose of preventing the straps from sliding off the shoulders. But, unlike the conventional arrangement, they are not interattached at the crossing point, such freedom from interattachment being necessary to allow the straps to be drawn apart sufficiently to clear the buttocks and upper thighs as the trousers are drawn forward on the thighs in the act of assuming the sitting posture.

As an alternative arrangement, the crossed relationship of the back straps of the suspenders may be discarded, as in Fig. 5, the straps being held in position on the shoulders by an elastic cross-piece 23.

In the conventional suspenders, the trousers may be lowered only by removing the suspender straps from the shoulders, or by disconnecting the back straps from the trousers. With my improved suspenders the straps are quickly extended in length by releasing the levers 16 and 22, thus permitting the slides 15 and 21 to slide downward on the front legs 5 and 6. Or, alternatively, the front button snap elements or connectors 15 and 20 may be disconnected from their supporting connectors, thus freeing the extensions 12 and 19 and allowing them to drop. This lengthening of the straps, by either method just described, permits the trousers to be dropped below the level of the buttocks. As the trousers

are slipped forward on the thighs while the wear-

er assumes the sitting posture, the straps assume a position on the lateral aspects of the thighs, completely out of the way.

The mechanical features of the various connecting and regulating devices described per se are all conventional, it being intended to utilize such standard materials and equipment as may be available. For instance, in addition to the device illustrated in Figs. 3 and 4, there are several different methods or devices available for use in attaching the extension 12 to the slide element 15, permitting quick and easy disconnection.

In Fig. 6 I show one of these several devices. A metal loop 24 is fixed to the front suspender strap 25, and a metal connector 26 is secured to the extension 25a of this strap. The connector 26 is provided with a tongue 27, which is formed with a keyhole slot 28, which is adapted to be coupled to the stud button 24a of the connector 24. By lifting the connector 26, so that the tongue 27 thereof will become disengaged from the stud button 24a the strap extension 25a will be released to drop. The metal loop 24 may be secured for adjustment to the suspender strap in any approved manner.

It is seen that I provide improvements in suspenders which permit of the wearer dropping his trousers without removing his coat and vest, thereby protecting his body from chilling while discharging a natural function, at the same time reducing the time element to a minimum, an important consideration in cases of emergency.

It is understood that various changes in the details of construction, their combination and arrangement, and in the use of available materials, may be resorted to, within the scope of this invention, as defined by the claim hereof.

Having described my invention, I claim as new:

A pair of suspenders comprising a pair of flexible straps adapted to be placed over the shoulders

of a wearer to provide forward ends to support the forward side of a pair of trousers and rear ends to support the rear side of the pair of trousers, the rear ends of said straps having connecting means for coupling to buttons on the waist band of the trousers, the forward ends having relatively long portions looped upon themselves, a slotted connector adapted to be coupled to the forward side of the waist band of the trouser through which each of the looped forward straps extends, a button snap element on the terminal of each of said forward looped straps, and a slideable connector releasably clamped to each forward looped strap and provided with a button snap element engageable by the first-named button snap element to provide a quickly detachable coupling between the forward terminal of the strap and the clamped connector, the looped straps providing long sliding connections to allow the wearer to drop his trousers without separating said straps from the trousers.

ROY S. ASHTON.
